UNITED STATES PATENT OFFICE

108,274

DESIGN FOR A COMBINED CLOCK FACE AND METRONOME

Albert H. Wolsfield, Philadelphia, Pa.

Application October 27, 1937, Serial No. 72,439

Term of patent 7 years

To all whom it may concern:

Be it known that I, Albert H. Wolsfield, a citizen of the United States, residing at Philadelphia, in the county of Philadelphia and Commonwealth of Pennsylvania, have invented a new, original, and ornamental Design for a Combined Clock Face and Metronome, of which the following is a specification, reference being had to the accompanying drawing forming a part thereof, in which

Figure 1 is a front elevational view of a combined clock face and metronome, showing my new design; and

Fig. 2 is a side elevational view of the same.

I claim:

The ornamental design for a combined clock face and metronome, as shown.

ALBERT H. WOLSFIELD.
